CLAIM

The ornamental design for a tote bag, as shown and described.

DESCRIPTION

FIG. 1 is a front perspective view of a tote bag, showing my new design.

FIG. 2 is a front elevational view thereof.

FIG. 3 is a rear elevational view thereof.

FIG. 4 is a right elevational view thereof.

FIG. 5 is a left elevational view thereof.

FIG. 6 is a bottom plan view thereof.

FIG. 7 is a top plan view thereof; and,

FIG. 8 is a front perspective thereof in an alternate collapsed storage configuration with the main body stuffed inside the front pocket.

The broken lines representing the stitching depict portions of the tote bag that form no part of the claimed design.

1 Claim, 7 Drawing Sheets
